UNITED STATES PATENT OFFICE.

SUMNER P. BARKER, OF SOUTH BEND, INDIANA.

INKSTAND.

SPECIFICATION forming part of Letters Patent No. 668,476, dated February 19, 1901.

Application filed May 23, 1900. Serial No. 17,828. (No model.)

To all whom it may concern:

Be it known that I, SUMNER P. BARKER, a citizen of the United States, residing at South Bend, in the county of St. Joseph and State of Indiana, have invented a new and useful Improvement in Inkstands, of which the following is a specification.

The objects of my invention are, first, to prevent evaporation and spilling of ink and, second, to provide an inkstand which, although normally securely closed by the automatic action of a valve, stands practically open at all times, admitting the pen into the ink with the same freedom as does the ordinary open inkstand. In securing these ends my invention contemplates an inkstand having a hollow or tubular stopper, the lower end being normally closed by a valve, which is thrust against it by a spring, and other details making up the device as a whole, as herein-after more minutely described and illustrated by the accompanying drawings, in which—

Figure 1 is view in central vertical section of the inkstand with stopper closed by the valve. Fig. 2 is a view in central vertical section of the inkstand with the valve opened by pressure upon the pen and the pen-point immersed in the ink. Fig. 3 is a perspective view of the stopper encircled by a rubber band, which serves as a packing between the stopper and the neck of the inkstand. Fig. 4 is a view of the valve which closes the stopper.

The manner of construction herein described is deemed most practical, although various changes may be made in form and manner of construction without departing from or evading the principles set forth in the claims.

Referring to the drawings, in which the reference characters denote corresponding and like parts in all views, A designates an inkstand with wide neck, preferably about one inch wide.

The letter B indicates the stopper, which may be made in two parts B and B' and united by some adhesive and insoluble substance. The parts may be made of glass or other suitable material. Part B is a thick hollow rim suitable to be gripped by the fingers and a thin shell or tube depending from its inner edge and tapering to an opening about three-

eighths of an inch in diameter and having a groove adapted to contain the rubber rim E, which serves as packing between the stopper and the neck of the inkstand. Part B' may be described as a short tube with a flaring or bell-shaped end adapted to fit into the top of the rim of part B, the small end corresponding in size with the opening in the lower end of the stopper, and depending into the central cavity of the stopper forms a recess between it and the outer walls of the stopper.

The valve C, which closes the end of the stopper B, may be made of thin sheet metal and is provided with an open framework or guiding-arms adapted to insure its proper adjustment as it closes, being normally held to its place by the spring D, one end of which supports the valve, while the other may thrust against the bottom of the inkstand or be retained in a groove or recess in its sides, or it may be applied in any other suitable manner.

A small disk of rubber or leather may be placed upon the valve and may be renewed at pleasure.

It will be observed that as the pen is introduced into the ink the valve is depressed by pressure upon the pen and that as the pen is removed the valve rises and closes the inkstand and that when the inkstand is overturned any ink that the stopper may contain will be retained in the recess around the opening.

Having thus described my invention, what I claim, and desire to secure by Letters Patent, is—

1. An inkstand having in combination there-with a hollow stopper adapted to securely close the same and provided with a central opening through which the pen may be thrust, a short tube depending from the top of the stopper around the opening forming a recess between the tube and the outer walls of the stopper, a valve thrusting against the lower end of the stopper having a guiding framework adapted to insure its proper adjustment, and a spring located within the inkstand adapted to hold the valve against the stopper with a yielding pressure all substantially as described.

2. An inkstand having an internal groove, a hollow stopper the walls of which extend downward tapering to an opening of smallest

2
practical size, a short funnel-shaped tube depending from the top into the central cavity of the stopper, a groove around the stopper a rubber packing therein, a valve adapted to 5 securely close the opening in the lower end of the stopper and having an open framework or guiding-arms embracing the tapering end of the stopper and a spiral spring normally retaining the valve against the stopper,

one end of which embraces the framework of the valve while the other is engaged by the groove in the walls of the inkstand, substantially as described and for the purposes set forth.

SUMNER P. BARKER.
